COMMUNICATION SYSTEM

Harry J. Nichols, Dayton, Ohio, assignor to International Business Machines Corporation, New York, N. Y., a corporation of New York

Application January 29, 1934, Serial No. 708,767

18 Claims. (Cl. 178—23)

This invention relates to synchronous communication systems and particularly to single impulse printing telegraph systems.

A general object of the invention is to provide an improved communication system whereby communications in typed form can be readily transmitted and received at remote points.

Another object of the invention is to provide a remote control system whereby commercial typewriters, with minor modifications and adaptations, can be utilized to type, send, and receive communications.

A further object is to provide a synchronizing system whereby the receiving machine can be automatically and instantly established in synchronism with the sending machine, and whereby synchronism is automatically re-established in case the departure in synchronism exceeds a predetermined amount or degree.

20 A further object is to provide a novel operating method in printing telegraph systems, whereby the operator at the sending machine can initiate operation of the receiving machine, establish proper conditions of synchronism, and thereafter control the printing operations of the receiving machine.

Another object is to provide a novel method and apparatus in a printing telegraph system in which single electrical signal impulses, distinguished in respect to time, are utilized to control the operation of the receiving machine from the sending machine.

A further object is to provide an improved arrangement of circuits and apparatus whereby the typewriter key board is controlled to prevent the sending of signals in improper order, or unwanted repeat signals, thereby to promote a high degree of accuracy in transmission.

40 A further object is to provide an arrangement of circuits and apparatus whereby one or more receiving machines can be quickly and reliably started automatically by the sending machine.

A further object is to provide means whereby the operator of the sending machine can be assured that the receiving machine is typing in proper case.

50 A further object is to accomplish the above objects of the invention by means of signal impulses suitable for transmission over telephone, telegraph, or radio communication systems without special adaptation of such systems.

Other objects and features will be in part obvious and in part hereinafter pointed out in connection with the following description taken in con-

nection with the accompanying sheets of drawings forming part of this disclosure.

In the drawings, Fig. 1 shows in diagrammatic form the circuits and apparatus which, together with the typewriter or printer typing mechanism, comprise a complete communication unit. The circuits are shown in the receiving condition, or more precisely, in readiness to receive.

Fig. 2 shows in diagrammatic form the particular parts of the circuit and apparatus used to control the key board and to prevent the transmission of false signals.

Fig. 3 is a diagram showing the arrangement of circuits, apparatus, and switches whereby automatic starting of the receiving machine is accomplished.

Fig. 4 shows in diagrammatic form a simplified arrangement for both sending and receiving shift and shift check signals, and for utilizing same for the remote control of the shift action of the receiving machine.

Fig. 5 is a similar diagram showing a simplified shift arrangement in which the shift and shift check functions are automatically combined.

In the several figures, like characters represent like parts.

General description

For purposes of description and as illustrative of a preferred embodiment of the invention, a complete communication unit is hereinafter described as comprising a typewriter, a typewriter control unit, and a distributor unit. The typewriter control unit is preferably mounted underneath and inside the typewriter frame. The distributor unit is preferably housed in a case located near the typewriter. The two units are conveniently connected electrically by a multiple conductor cable.

The complete communication units may be used in pairs, one unit sending while the other receives, and vice versa, or they may be connected in such a manner that the sending unit controls a group of receiving units. Units may be connected for communication purposes by means of general communication systems, such as a telegraph, telephone, or radio system, or simply by a pair of wires, or one wire and ground.

In Fig. 1, the apparatus comprising the typewriter control unit is included within the dot-dash rectangle; all other apparatus is included in the distributor unit.

The apparatus shown in Fig. 1 performs the functions of transmitting and receiving synchronizing and printing signals, and utilizing these

signals, and responsive local impulses, for various starting, synchronizing, selecting, and control purposes. The local impulses are distributed to their proper circuits by the rotary distributor.

5 Referring now to Fig. 1 in detail, the rotary distributor 15 consists of a series of insulated metallic segments 16 and a solid metallic ring 17 mounted on a suitable disc of insulating material (not shown). A rotary contactor 18 is frictionally driven by drive motor 19 and contacts each segment once during each revolution in a well understood manner. The drive motor 19 must be of exactly uniform speed, or suitable governing means must be employed to obtain a highly 15 uniform speed.

The rotary contactor 18 is shown in the rest position on number 2 segment. A release magnet 20, functioning as a start-stop means, is provided to stop and release rotary contactor 18 in accordance with the invention, and for illustrative purposes is shown with its armature 21 in engagement with contactor 18. Armature 21 also operates spring contacts 25 and 26 which function in connection with starting operations. Release magnet 20 is provided with a low impedance winding 22 and a high impedance winding 23 connected in series aiding relation. Across the terminals of winding 23 is connected storing condenser 24. Release magnet 20 is of the quick 25 acting, slow release type which responds quickly to a short current pulse, but holds for a protracted period, hence if supplied with properly timed impulses, continues to hold in the operated position so long as such pulses are regularly received, but drops out shortly after the pulses cease, or in case the pulses are too greatly diminished. An improved relay or magnet of this type, which may be termed a pulse sustained relay, is described in detail in my co-pending 30 patent application, Serial No. 672,161 filed May 22, 1933.

The power for transmission purposes and for the operation of the various relays and magnets is obtained from any suitable direct current 45 source, preferably from a rectifier assembly as shown.

The output of the rectifier is applied to the terminals of a four section voltage divider 44, as shown. The positive bus 42 is connected to the 50 positive terminal of voltage divider 44, and the negative bus 40 to the negative terminal. The zero bus 41 is connected to the zero or ground terminal between sections 44a and 44b of voltage divider 44, section 44a thus furnishing in a well 55 understood manner negative bias for the grid 133 of electronic relay 130.

The elements of electronic relay 130, which is of the grid controlled, gaseous discharge type are the grid 133, the cathode 134, and the anode or 60 plate 135, all contained in an envelope 132 containing gas or vapor at low pressure, as is well understood.

In series with the anode-cathode circuit of relay 130 is the cut-off relay 170, connected as 65 shown, with winding 171 shunted by variable resistor 172 and provided with spring contacts 173 and 174. As is well known, the grid of a grid controlled gaseous discharge tube is normally 70 unable to stop the discharge thru the anode circuit when once started, and in general, either the plate current must be cut off, or else the plate must be rendered negative in respect to the cathode. It is preferred to cut off the plate current after a properly timed interval by utilizing cut-off relay 170 to open contacts 173-174. The

variable resistor 172 permits of very exact timing of the cut-off interval, and the location of the relay in the circuit as shown is found to give quick and reliable de-ionization of electronic relay 130. A spark suppressor arrangement may be 5 connected across contacts 173-174 as shown to reduce sparking to a negligible degree.

The non-repeat relay 140 is connected in circuit only while sending, and has for its principal function the prevention of the transmission of 10 false signals. It will be explained in detail hereafter in connection with Fig. 2.

The multiple switch relay 160, controlled by send-receive switch 190, provides the automatic switching operations required to change from 15 sending conditions to receiving conditions and vice versa. It is provided with a single winding 161 and five sets of contact springs numbered 1-14 inclusive. In order to simplify the diagram, these contacts are shown in their natural locations in 20 the circuit. The winding of relay 160 is connected in series with the windings of release magnet 20 across section 44d of the voltage divider reducing the voltage across these windings and economizing on holding current. 25

The start relay 50 is connected across the line on receiving so as to respond to received signals. It is of the pulse sustained type and performs various switching operations to start the receiving machine automatically. It will be more fully 30 described hereinafter in connection with Fig. 3.

The input transformer 32 is connected to the line on receiving by start relay 50. It applies the signal pulses to the grid of electronic relay 130.

Included in the typewriter control unit is the 35 key solenoid assembly suitably mounted, consisting of a bank of solenoids 158, one for each operating key 156 of the typewriter or printer. The plunger of each solenoid is connected to its associated key lever by means of a spring link 184. 40 This construction provides smooth operation of the printer actuating levers, and improves the pull characteristics of the solenoids.

Each key lever 156 has associated with it an individual key switch 157, of break-make type, 45 actuated by an individual insulated push rod 155. The armature spring of each key switch is connected to an individual segment, the make springs being connected to the common key-switch bus 138 as shown, while the break springs are connected to the individual solenoids. A universal bail 153 is positioned below and transversely across the row of key levers, being held in light contact therewith by a retractile spring (not shown). When any key is depressed, bail 153 50 closes auxiliary switch 154 by means of push rod 155. Auxiliary switch 154 forms a part of the key-latch and non-repeat arrangement. 55

The key latch 151 consists of a pivoted, universal latch bar extending across the ends of all 60 the key levers, the ends of which are provided with a square projection as shown. A retractile spring 183 attached to latch 151 so as to obtain proper leverage normally holds the latch out of engagement with the key levers. The key latch 65 magnet 150 actuates the key latch, as will be more fully explained in connection with Fig. 2. The send-receive switch 190 is a two-position switch which switches certain circuits from sending to receiving conditions, as required. 70

Sending circuits and operations

Referring to Fig. 1, the transmission of synchronizing signal impulses is accomplished as follows:

Assume that drive motor 19 is operating and tending to rotate rotary contactor 18 by a friction drive but that the contactor is held in the rest position on segment 2 by armature 21 of release magnet 20. To start sending synchronizing signals, send-receive switch 190 is thrown to the S or send position. This completes a circuit from positive bus 42 thru winding 22 and condenser 24 of release magnet 20 via contacts 192-191 of send-receive switch 190, thru winding 161 of relay 160 to the voltage divider between sections 44c and 44d. A current pulse thru this circuit operates relay 160, breaking contacts 2-3, 5-6, 8-9, 11-12, and making contacts 1-2, 4-5, 7-8, 10-11, 13-14. Release magnet 20 is also energized, attracting armature 21 which releases rotary contactor 18. As condenser 24 becomes charged a small steady current limited mainly by the resistance of windings 23 and 161 flows thru these windings providing sufficient holding current to hold relay 160 and magnet 20 in the operated condition. A strong operating pulse followed by low holding current is thus provided.

On being released by armature 21, contactor 18 is set in rotation by the friction drive and takes up the uniform speed of the motor drive shaft. When contactor 18 reaches segment 1, a circuit is completed from positive bus via contacts 8-7 thru inductance 161, via contacts 4-5 to segment 1; thence via contactor 18 to ring 17 and via contacts 2-1 and 18-11 thru line and return to zero bus via ground. For the duration of contact with segment 1, current flows thru the circuit just traced, and a signal impulse is sent to the line. This periodic signal impulse, which is repeated for each revolution of contactor 18, constitutes the synchronizing signal.

Inductance 161, which is included in the circuit transmitting the synchronizing signal, is designed to match the inductance of winding 141 of non-repeat relay 140 which is included in the circuit transmitting printing signals, hence the amplitude and wave form of the synchronizing signals and printing signals are substantially identical.

To commence sending printing signals, send-receive switch 190 is thrown to the S position, and synchronizing signals are sent to the line for a few seconds to permit the receiving machine to come to synchronism as hereinafter described. Printing signals may then be sent by depressing the typing keys of the typewriter as for ordinary typing.

Referring to Fig. 2, and assuming that key A is struck, a printing signal is transmitted as follows: As the key is depressed, the middle and lower contacts of its own particular key switch are closed, thus connecting sending bus 138 to a particular segment, in this case to segment 4. When rotary contactor 18 arrives at segment 4, a circuit is completed from positive bus 42 through winding 147 of non-repeat relay 140 via contacts 141-142 of same, to send bus 138, via contacts of closed key switch 157 to segment 4, via contactor 18 to ring, thence via contacts 2-1 and 10-11 to line and return to zero bus via ground. A current pulse flows through this circuit including the line, its duration being determined by the time of contact of contactor 18 with the connected segment. Such aperiodic signal impulses, distinguished in respect to the time interval from the preceding synchronizing signal, constitute the printing signals.

Concurrently, as the key lever nears the bottom

of its stroke, the printing mechanism (not shown) of the typewriter is tripped, and the typewriter immediately types the proper character to furnish a local copy of the message.

Key latch and non-repeat arrangement

Instantly upon the depression of a printing key, the key latch arrangement is operated as follows: Each time a key is depressed, universal bail 153 closes the contacts of auxiliary switch 154 by means of push rod 155. The lower spring of the auxiliary switch is connected to ground and the upper spring is connected via contacts 194-193 to contact 145 of non-repeat relay 140. Upon the closing of the auxiliary switch contacts, a circuit is completed from ground via contacts of auxiliary switch 154 and contacts 194-193 and 155-144 through winding 152 of latch magnet 150 to tap 44f of voltage divider 44. A current pulse through the circuit just traced operates latch magnet 150 which by means of spring link 184 and crank arm 189 quickly hooks the pivoted latch member 151 over the end of the depressed key lever, latching it down. This is done so quickly that the finger can be removed from the struck key with great rapidity without danger of premature release of the key lever.

As illustrated in Fig. 2, the latch member 151 not only serves to hold down the depressed key, but also serves as an interlock to hold all other keys against being depressed, thus guarding against depressing a second key before the printing signal from the connected segment is sent to the line. This arrangement has the advantages of not requiring additional interlocking means to obtain this feature, and also in that the interlocking feature only comes into play during sending, the key board being entirely free when receiving. As a consequence, less actuating force for the key levers is required permitting smaller key solenoids to be employed.

The printing impulse previously described, in addition to sending a printing signal to the line, also performs an important function in the key-release and non-repeat operations. The printing impulse flowing thru winding 147 energizes non-repeat relay 140, which operates, opening contacts 141-142 and 144-145, and closing contacts 142-143 and 145-146. Opening contacts 141-142 disconnects winding 147 which is too low in resistance to place directly across the line. Opening contacts 144-145 cuts holding current off winding 152 of latch magnet 150 which releases, thus permitting retractile spring 183 to draw latch 151 away from the key levers, thus releasing all keys insofar as the latch arrangement is concerned. It is possible, however, that a key may be inadvertently held down by the finger after being released by the latch, and in this event, it is necessary to prevent false repeat signals from being sent to the line. Therefore, when contacts 145-146 are closed, send bus 138 is connected via these contacts to ground, hence any connected segment, except the synchronizing segment, is placed at zero potential, and no more printing signals can be sent to the line so long as contacts 145-146 remain closed. Closing contacts 142-143 supplies holding current for winding 148 thru a circuit from voltage divider tap 44f through winding 148 via contacts 143-142, 146-145, 193-194 and auxiliary switch 154 to ground. When the depressed key is released, auxiliary switch 154 is opened, taking holding current off the non-repeat relay, which releases and opens contacts 143-142 and 146-145.

75

This completes the cycle, and leaves all sending circuits in normal condition.

It will be noted that the key latch 151 serves as a key board lock during the brief but variable 5 interval from the instant a key is depressed until the signal impulse is transmitted by rotary contactor 18, whereupon the non-repeat relay cuts off the current from the latch magnet. Simultaneously, the non-repeat relay grounds the send 10 bus and hence any connected segment, preventing further signals being sent to the line until all keys are released. The result is that only one signal can be sent for each cycle of operation 15 of a key lever. This constitutes the non-repeat feature. In case continued repeat signals from a key are desired, it is only necessary to connect the key latch switch of that particular key to positive bus instead of to the send bus, which 20 exempts that particular key from the non-repeat feature.

In normal operation, the keys are depressed and released quickly, and the key board is released for further writing practically instantly 25 when the signal is sent to the line.

25 Starting circuits and operations

Referring to Figs. 1 and 3, and more particularly to Fig. 3, the apparatus primarily involved in receiving both synchronizing and printing signals comprises start relay 50, the primary winding 33 of input transformer 32, and their associated circuits and switches. Start relay 50, preferably of the pulse sustained type previously described, is preferably provided with a low impedance operating winding 56 and a high impedance holding winding 57 wound on the same core and connected in series aiding relation. Across winding 57 is connected storing condenser 58. The impedance of the windings and condenser in combination should preferably match the impedance of the transmission line or connecting transmission circuits. As compared to release magnet 20, start relay 50 need not be as powerful, since it is required only to operate 40 its own contact springs, and need not respond to the first pulse received. Likewise, it is not essential that start relay 50 have separate operating and holding windings, altho there is in some cases an advantage in having a separate operating winding, both in respect to a more prompt 45 response and in compensating for primary winding 33, as more fully explained hereinafter. Relay 50 is provided with a pair of make contacts 51-52, and a set of break-make contacts numbered 53-55 inclusive. In parallel with make contacts 51-52 are connected make contacts 13-14 which may be actuated either by multiple switch relay 160 as indicated above, or manually by send-receive switch 190, as may be preferred. Contacts 13-14 function in the starting 50 of drive motor 19 when initiating sending conditions.

The operation of the automatic start arrangement is as follows: The incoming signals, assumed to be the synchronizing signals, are received at the line terminals 30, 31 and traverse the circuit from terminal 30 via contacts 11-12 65 via contacts 55-54 thru winding 56 and condenser 58 to terminal 31. The pulses thru this 70 circuit build up the charge on condenser 58 faster than the charge leaks off thru winding 57, thus energizing relay 50 which pulls in its armature on a signal pulse, opening contacts 55-54, and closing contacts 54-53, and 52-51. Opening 75 contacts 55-54 removes the short circuit on

primary 33, which thus becomes capable of functioning. Closing contacts 54-53 short circuits winding 56, whose impedance is thus removed from the signalling circuit to compensate for the addition of the impedance of winding 33. 5 Closing contacts 52-51 connect power to drive motor 19 and, if required to the typewriter motor in instances where electric driven typing machines are employed. It is to be noted (Fig. 3) that a two-way manual switch SW is provided 10 for the typewriter motor, so that this motor may be started automatically if not already running.

So long as signals are regularly received, relay 50 remains operated; if signalling is discontinued, or interrupted, the charge on condenser 15 58 is not replenished, and relay 50 releases, restoring all circuits to initial conditions. This completes the cycle of operations of the automatic start arrangement, which provides means for starting up the receiving machine in the absence of attendants, after which messages may be received in the usual manner. It also provides for shutting down the receiving machine during 20 idle periods.

It is to be noted that the arrangement illustrated 25 assumes that power is already turned on the rectifier apparatus and also on the cathode of the electronic relay 130. This is the preferred arrangement where messages are being sent back and forth frequently, since there is no need to 30 wait until the rectifier and electronic relay tubes are warmed up before starting transmission. Where messages are set infrequently, or the warm up period is negligible, or the saving by not having the tubes lighted is a consideration, 35 start relay 50 can be utilized to turn current on the rectifier, or electronic relay, or both, as desired. Such variations in switching arrangements to meet various operating conditions will be evident to those skilled in the art and are 40 clearly within the scope of the invention.

Synchronization

The operations connected with the sending of the periodic synchronizing signals have already 45 been described. Referring again to Fig. 1, the operations connected with receiving and utilizing these signals are as follows: The first step is that of establishing synchronism of rotary contactor 18 of the receiving machine with the received synchronizing signals. Since the periodic synchronizing signals are sent from a particular segment, termed the synchronizing segment, of the sending machine, it follows that for complete synchronization, the rotary contactor at the receiving machine must arrive at the leading edge 50 of the synchronizing segment each time a synchronizing signal arrives from the sending machine. 55

At the receiving station, the synchronizing signals 60 are received at the line terminals 30 and 31, and upon the operation of start relay 50 are applied to the primary 33 of input transformer 32. Concurrently, the drive motor is started up, as previously described. The synchronizing signals thru primary 33 induce a voltage across secondary 34 and shunt resistor 35, and with proper polarity, alter the bias voltage on grid 133 and trigger off electronic relay 130, which becomes ionized and conducting, thus permitting 70 a strong current flow in its plate circuit. The contactor 18 being held at rest on segment 2, a circuit is completed from zero bus via contacts 173-174, thru relay winding 171 via center tap 136 of power transformer 137 to cathode of re- 75

lay 130 thence to plate 135, via contacts 3-2 to ring, via contactor 18 to segment 2, via contacts 26-25 thru condenser 24 and winding 22 to positive bus. A strong current pulse flows 5 thru this circuit, operating release magnet 20 and thereafter cut-off relay 170, which opens contacts 173-174, terminating the pulse. The armature 21 is quickly pulled in, releasing contactor 18 and opening contacts 25-26. The 10 pulse of current thru condenser 24 charges that condenser, providing holding current for relay 20, and preventing the release of armature 21. Upon release, contactor 18 is set quickly in motion by its friction drive, and is thereafter 15 rotated at uniform speed by drive motor 19. Contactor 18, having been released from segment 2 in response to a pulse occurring concurrently with the passage of the contactor across segment 1 at the sending station would arrive 20 at segment 1 before the arrival of the next synchronizing signal, were it not for a slight delay in the operation of relay 20 and a slight amount of slip of the friction drive. Because of these delays, the lead provided by starting contactor 25 18 from segment 2 enables the contactor to arrive at the leading edge of segment 1 as the next synchronizing signal is received. This synchronizing signal energizes electronic relay 130 as before, but this time the local circuit is completed 30 via segment 1, the circuit of segment 2 having been opened at contacts 25-26 by the operation of release magnet 20. The current pulse through the completed circuit replenishes the charge on condenser 24, maintaining release magnet 20 in the operated position, hence armature 21 does not interfere with contactor 18 which continues in rotation so long as it arrives on segment 1 in unison with the synchronizing signal. Means are provided for adjustment of the 35 starting position of contactor 18, and also of the frictional driving force, thus enabling exact timing of the starting revolution to be made. In practice, it is found that with proper adjustments, synchronism is accurately established on the first revolution. Thereafter, the maintenance of synchronism depends on the preservation of precisely uniform speed of the drive motors at the sending and receiving machines. Should, for any reason, unison within approximately 40 one-half segment width be departed from, or the incoming synchronizing signals be interrupted beyond a predetermined interval, contactor 18 is stopped on the rest segment by reason of release magnet 20 dropping out 45 through lack of sufficient holding current. The synchronizing procedure is then repeated when the next synchronizing pulse is received. Thus synchronism, if lost, is automatically re-established.

50 The system of synchronizing herein described is particularly adapted to communication systems to be operated in regions having a common power system of accurately controlled frequency, in which circumstances good results are obtained 55 from synchronous drive motors supplied with power from the common system. As is well understood, the employment of synchronous motors in such installations assures virtually perfect isochronism, and if the receiving machine is 60 established in the proper phase relation, synchronism with the sending machine will continue practically indefinitely. For installations where suitable synchronous power is not available, the 65 synchronizing system disclosed in my copending 70

application Serial No. 672,161 filed May 22, 1933 may be preferred.

Receiving circuits and operations

Synchronism having been established as previously described and the rotary contactors at the receiving and sending stations being in unison, printing signals may be sent to the receiving station as described in connection with sending operations. 5

Referring to Fig. 1, the printing signals when received are applied to primary 33 as previously described, and potential variations from secondary 34 trigger off electronic relay 130 which becomes conducting. A circuit is thus completed 10 from zero bus via contacts 173-174, thru relay winding 171 via center tap 136 of power transformer 131 to cathode of relay 130, thence to plate 135, via contacts 3-2 to ring as before described, and thence via contactor 18 to the segment with which it is in contact. The response of electronic relay 130 to signals being practically instantaneous, and contactor 18 being in unison with the corresponding member at the sending station, it is evident that the contacted receiving 15 segment will correspond to the sending segment. From this segment, of which segment 4 may be considered an example, the circuit continues via the middle and upper contacts of key switch 157 20 thru winding 159 of key magnet 158 to key magnet bus 139 via contacts 9-8 to positive bus. The pulse thru this circuit energizes key magnet 158 whose plunger is attracted, stretching spring link 184 which pulls down the key lever to which it is attached. The key lever trips the typewriter or printer mechanism (not shown) printing the selected character. As the key lever 25 nears the end of its downward travel, push rod 155 opens the key switch contacts. Owing, however, to inertia of the key lever and other retarding effects, the circuit is actually broken by the 30 opening of contacts 173-174 by cut-off relay 170 which is preferably adjusted to cut off the current just short of the termination of the line signal. With perfect unison, the circuit is broken 35 before contactor 18 leaves the connected segment. 40

Shift and shift-check arrangement

Referring to Figs. 4 and 5, which illustrate a 50 method and apparatus for controlling and checking the shift function of the receiving typewriter or printer, in order to simplify the description of this feature and to facilitate the tracing of circuits, the diagrams are shown schematically with 55 some parts of the circuits in abbreviated form. The manner in which this feature is incorporated with other apparatus shown in Fig. 1 will be clear by the circuits and apparatus shown in the diagrams considered in connection with Fig. 1. 60 In general, circuits used in sending operations are shown in full lines while those used in receiving only are shown by dash lines. The switch contacts are shown in position for sending. 65

Referring to Fig. 4 in particular, the diagram illustrates an embodiment of the invention in which the shift and shift-check functions are distinct. The shift key lever is similar to the printing key levers 156, and is similarly provided 70 with its individual key switch 157 and key magnet 158. The fork member 155b indicates the function of the key lever in actuating the shift mechanism (not shown). A shift mechanism suitable for use with this invention is shown in 75

my copending application Serial No. 701,644 dated December 9, 1933.

In connection with the present description, it is to be understood that the shift mechanism alternately shifts to the upper case and lower case characters on successive operations of the shift key. Otherwise stated, each time the shift key is depressed, the shift mechanism shifts case, and remains locked in that case until the succeeding depression of the shift key. This mode of operation dispenses with the need for holding the shift key depressed manually while upper case characters are being typed. The receiving machine is controlled to perform the shift and other printing movement operations by printing signals as previously described. The particular point to be noted in connection with the present description is that if the receiving machine is left in the wrong case position, or due to some cause is erroneously shifted, upon starting up the receiving machine by remote control, the proper keys of the receiving machine would be actuated by the sending machine, but the characters would be typed in the wrong case, with consequent confusion in the message. Hence assurance of conformity in the typing case at the receiving machine is highly desirable and means are provided for securing such conformity.

Conveniently located on the key board is another key 256 designated as the check key, which is provided with its individual key switch 257, but does not actuate any mechanism of the typewriter and is used only for transmitting signals. Attached to some part of the typing mechanism which moves into predetermined positions related to the shift case, as for example, type basket 201, is an actuating finger 202 adapted to actuate shift switch 203, as indicated. The upper case position of type basket 201 is indicated in broken lines. When the type basket is in the lower case position, the contacts of shift switch 203 are open; when the type basket is in the upper position they are closed. The remaining parts or their equivalents have been described in connection with Fig. 1.

The operation is as follows: The sending machine is placed in a predetermined case position, such as the lower case position, and to check the shift position of the receiving machine, and correct same if not in conformity with the sending machine, check key 256 is depressed. A circuit is thus closed from positive battery via contacts 8-7 via send bus 138, lower and middle contacts of key switch 257 to segment 16c. When rotary contactor 18 arrives at segment 16c, the circuit is completed to ring 17 thence to line and return via contacts 11-10 to negative battery. A current pulse in this circuit during the duration of contact with segment 16c sends a printing signal to the receiving machine, which is assumed to be synchronized, with its rotary contactor 18 likewise in contact with segment 16c.

At the receiving machine the operation is as follows: The printing signal passes from line terminal 30 via contacts 11-12 thru relay 130 to line terminal 31. Relay 130 is thus energized, completing a local circuit from negative battery via contacts 130a, via ring and rotary contactor 18 to segment 16c, via middle and upper contacts of key switch 257, via conductor 260, contacts of shift switch 203 (assumed to be closed) and conductor 261 thru key magnet winding 159 to receiving bus 139 via contacts 9-8 to positive battery.

It having been assumed that the contacts of

shift switch 203 are closed, that is that the receiving machine is in the upper case (non-corresponding) position, key magnet 158 is energized, operating key lever 156 which trips the shift mechanism and brings the receiving machine into the lower case position and hence into conformity with the sending machine. Should, however, the receiving machine already be in lower case, the circuit would be incomplete at the contacts of shift switch 203 and the receiving machine would not be shifted. Thereafter operation of the shift key lever 156 will cause corresponding shift of case at both sending and receiving stations through segment 16b, in the same manner as described above for the printing key levers.

It is to be understood that variations in the location and arrangement of the shift switch and other details may be found convenient in adapting the invention to various typing mechanisms, and such variations will be readily perceived by those skilled in the art and are within the scope of the invention. Likewise, the method and apparatus disclosed are readily adapted to other machines than that shown in Fig. 1, and to groups of machines under the remote control of a sending station.

In the embodiment of the invention just described, shift checking may be accomplished from one shift position of the sending machine, but not both. In the embodiment now to be described, shift checking can be accomplished from either shift position, the check key is eliminated, and checking is accomplished automatically upon the operation of the shift key. Referring to Fig. 5 in detail, shift key 156 is provided with a key magnet 158 but no key switch, the transmission of signals being performed by the shift switch. The finger 202 carried by a convenient part of the typing mechanism as above described, is provided with a cross piece 204 carrying at each end an insulated jockey roller indicated by 205a and 205b respectively. Shift switch 203 comprises one set of alternate make contacts, designated by 203a, and two sets of break-make contacts designated as 203b and 203c respectively. The connections of these contacts will become apparent in tracing out the sending and receiving circuits.

In the first embodiment of the shift-check arrangement, it is to be observed that the mechanical shift action had been completed before the check signal was transmitted. To avoid confusion in transmission, because of the variable interval between the depression of the shift key and the transmission of the shift signal, it is desirable in the second embodiment to provide means to insure that the mechanical shift action is completed before the shift signal is transmitted to the receiving machine. To this end, it is provided that during the mechanical shift action, preparations are made to transmit the shift signal, but the signal is only transmitted after the completion of the mechanical shift action, irrespective of the manual operation of the shift key. Condenser 206 is provided to store the energy to transmit the shift signal during the variable interval prior to transmission.

The operation is as follows: To shift, the shift key is depressed in the usual manner, and the shift mechanism (not shown) is tripped to shift the typebasket (for example). Assuming that the typebasket is moved upwards, as jockey roller 205a passes switch 203a, the middle contact is momentarily closed on the upper contact, and then the contacts open as the jockey roller slips

past. During the moment that the contacts are closed a circuit is completed from positive battery via contacts 8-7 thru conductor 262, via upper and middle contacts of switch group 203a, 5 thru conductor 263 and condenser 206 to negative battery. Condenser 206 is thus charged to the potential of battery 44. As the typebasket completes its upward travel, jockey roller 205b closes the middle and upper contacts of switch 10 group 203c.

When rotary contactor 18 reaches segment 16c, a circuit is completed from the positively charged side of condenser 206 thru conductor 263, via upper and middle contacts of switch group 203c 15 to segment 16c, via contactor 18 to ring thence to line terminal 31, thru line and return, via contacts 11-10 to negative side of condenser 206. Condenser 206 discharges thru this circuit, sending the shift signal to the line.

20 At the receiving machine, the operation is as follows: The line signal energizes relay 130 as before described. Assuming that the receiving machine is in the lower case position as shown in Fig. 5, when relay 130 closes its contacts, a 25 local circuit is completed from negative battery via contacts 130a to ring, via contactor 18 to segment 16c, thence via middle and lower contacts of group 203c and conductor 261 thru winding 159 of key magnet 158 to receive bus 139, via 30 contacts 9-8 to positive battery. A current pulse thru this circuit energizes key magnet 158 which pulls down the shift key and trips the shift mechanism, shifting the typebasket to the upper position. The receiving machine is thus brought 35 to conformity with the sending machine as regards case.

Assume on the contrary that the receiving machine had been left in the upper shift position. In that event the receiving circuit would have 40 been broken at the contacts of group 203c, and the key magnet 158 would not be energized, hence the receiving machine would remain in the upper shift position and would thus conform with the sending machine.

45 Were it assumed that the sending machine was initially in the upper shift position, the operation would be the same, except that the shift signal would have been transmitted via switch group 203b and segment 16b, and at the receiving machine the local pulse would have been applied thru the corresponding circuit.

It is to be noted that with the arrangement shown, by selecting a suitable size for condenser 206, it will be fully discharged while transmitting the shift signal to the line, hence no especial provision against repeat signals is necessary.

It will be apparent that my invention provides a communication system particularly adapted to the utilization of commercial typewriters for the 55 sending, receiving and printing functions of a printing telegraph system. Also that various features of the invention may be readily adapted to uses other than those illustrated.

While the methods herein described, and the 60 forms of apparatus for carrying these methods into effect, constitute preferred embodiments of the invention, it is to be understood that the invention is not limited to these precise methods and forms of apparatus, and that changes may 65 be made in either without departing from the scope of the invention which is defined in the appended claims.

What is claimed is:

1. In a synchronizing system for the remote 70 control of apparatus, in combination, control-

ling means for producing periodic electrical synchronizing impulses, transmission means for said impulses, receiving means responsive to said impulses, means for establishing and maintaining synchronism of said controlled member with the 5 controlling means within predetermined limits including a controlled rotary member, drive means for rotating said controlled member isochronously with respect to said synchronizing impulses, start-stop means for said controlled 10 member responsive to received synchronizing impulses for releasing said controlled rotary member for operation by said drive means, and electrical energy storing means for sustaining the 15 operation of said start-stop means.

2. A system for synchronizing remotely situated apparatus which comprises means for producing periodic single impulses, transmission means for said impulses, a controlled element, 20 drive means adapted to move said controlled element isochronously with respect to said impulses, release means for said controlled element operated in response to said periodic impulses and adapted to release said controlled element from a predetermined phase position for operation by 25 said drive means and to thereby establish synchronism of said controlled element with said periodic impulses, and electrical storing means associated with said release means and adapted to sustain the operation of said release means 30 so long as synchronism is maintained within predetermined limits.

3. A system for synchronizing remotely situated apparatus which comprises controlling means for producing periodic synchronizing impulses, transmission means, a controlled element, 35 drive means adapted to move said controlled element isochronously with respect to said synchronizing impulses, start-stop means responsive to said synchronizing impulses and adapted to establish the driving of said controlled element by said drive means in synchronism with said synchronizing impulses, and a capacity element associated with said start-stop means for storing energy from said synchronizing impulses to 40 maintain said start-stop means in the start position during the continuance of said synchronizing impulses and while said controlled element continues to operate isochronously with respect thereto.

4. In a synchronizing system, in combination, a controlled element, drive means adapted to move said controlled element isochronously with respect to incoming periodic synchronizing signal impulses, and start-stop means for said controlled element comprising an electromagnet operating in response to said incoming signals and an electrical storing element cooperating with said electromagnet to sustain the operation of said electromagnet during the intervals between 55 the arrival of successive synchronizing impulses.

5. In a synchronous system, in combination, controlling means producing periodic synchronizing signal impulses, transmission means for said impulses, a rotary contactor, drive means adapted to rotate said rotary contactor isochronously with respect to the synchronizing impulses, control means energized by said impulses to initiate rotation of said rotary contactor by said drive means, and control means associated with said control means to maintain the said control means energized during the intervals between the arrival of successive synchronizing impulses.

6. A system for synchronizing remotely controlled apparatus which comprises controlling 75

- means producing periodic synchronizing signals, transmission means for said signals, a controlled element to be synchronized, drive means adapted to move said controlled element at substantially constant speed isochronously with respect to said signals, start-stop means adapted to prevent the driving of said controlled element by said drive means and to release said element for operation by said drive means in predetermined relation with a synchronizing signal to thereby establish synchronous relation between said controlled element and said signals, control means for said start-stop means responsive to and operated by said signals to enable said controlled element to be moved in synchronism with said signals, and means to maintain the said control means operated during the intervals between the arrival of successive synchronizing signals.
7. A system for synchronizing remotely situated isochronous elements which comprises a controlling element for producing periodic single impulses, a controlled element, drive means for moving said controlled element isochronously with respect to said impulses, release means for said controlled element energized by said periodic impulses to provide for the driving of said controlled element by said drive means to thereby establish synchronism of said controlled element with said controlling element, and means operable while synchronism exists for maintaining said release means energized, and to deenergize the release means in event the departure from synchronism of said controlled element exceeds a predetermined degree for resynchronizing said controlled element with said controlling element.
8. A system for synchronizing remotely situated isochronous elements which comprises a controlling element producing a single periodic impulse, a controlled element, means for moving said controlled element isochronously with respect to said impulses, start-stop means actuated in response to said periodic impulses for releasing said controlled element for operation by said isochronous means, a charge storing device associated with said start-stop means, means for supplying said charge storing device with a charge varying in an amount upon a departure of said controlled element from synchronism, and means including said start-stop means for causing the operation of said controlled element to be interrupted when the charge in said charge storing device falls below a predetermined limit.
9. In a synchronous system, the method of automatically establishing and maintaining synchronism between remotely situated elements which comprises the steps of sending impulses indicative of a predetermined phase position of an isochronous controlling element, receiving said impulses, releasing an isochronously moving controlled element from a predetermined phase position directly in response to said received impulses thereby to establish synchronism, storing energy controlled in response to said impulses, and interrupting operation of said controlled element when said stored energy decreases beyond a predetermined limit.
10. A system for synchronizing remotely situated periodic elements, which comprises controlling instrumentalities producing timed single impulses of definite periodicity, a controlled element, drive means for said controlled element moving isochronously with respect to said impulses, release means whereby said timed impulses are utilized to release the controlled element from a definite phase position thereby to

establish synchronism with the timed impulses, and electrical storing means cooperating with said release means to resynchronize said controlled element in event the departure from synchronism of the controlled member exceeds a predetermined degree. 5

11. A system for synchronizing remotely situated isochronous elements, which comprises a controlling element producing periodic single impulses, a controlled element, an isochronous drive member for said controlled element, start-stop means for said controlled element actuated by said periodic impulses for releasing said controlled element in predetermined time relation to said impulses to be driven by said drive member in synchronism with said controlling element, and electrical storing means cooperating with said start-stop means to stop and re-synchronize said controlled element in event the departure from synchronism of the controlled member exceeds 20 a predetermined degree.

12. A system for synchronizing remotely situated isochronous elements, which comprises a controlling element producing a single periodic impulse during each cycle of movement, a controlled element of like period, electromagnetic release means effective to establish phase-synchronism of said controlled element with said periodic impulses, and control means for said release means including a condenser connected in parallel with a winding of said electromagnet, and means for energizing said control means to cause withdrawal of said release means from interference with the movement of the controlled element including an energizing circuit for the control means completed in a predetermined phase position of said controlled element. 30

13. A synchronous communication system comprising a typewriter having a keyboard, switching means associated with said typewriter whereby specific circuits are closed when each key of said typewriter is depressed, means for transmitting periodic single synchronizing signals and means for transmitting aperiodic single printing signals in accordance with the operations of said switching means, a transmission circuit, means for receiving the transmitted synchronizing and printing signals, an electrical energy source, means for forming current impulses corresponding to said signals, a controlled element, drive means engageable with said controlled element, release means utilizing said current impulses corresponding to the synchronizing signals to control the engagement of said controlled element with said drive means to thereby establish synchronism, a second typewriter, actuating means for said second typewriter, and selector means for utilizing the current impulses corresponding to the printing signals to energize selectively the typewriter actuating means. 45 50

14. In printing telegraph apparatus, in combination, a plurality of printer actuating levers, printing signal transmitting means, auxiliary switching means operable by any one of the plurality of actuating levers, lever latch means controlled by said auxiliary switching means adapted when in the operated position to latch down any of the actuating levers in the depressed position and to latch up the other actuating levers in their normal positions, electromagnetic operating means for said latch means, and relay control means for said latch operating means adapted to de-energize said operating means when a printing signal is transmitted. 60 65

15. In printer key boards, in combination, a 75

plurality of printer actuating levers, auxiliary switching means operable upon the depression of any one of the actuating levers, lever latch means adapted to latch down a depressed actuating lever and simultaneously to latch up the other actuating levers, electromagnetic latch operating means, relay control means for said latch operating means, and electrical connections between said auxiliary switching means, said latch operating means and said relay control means, the electrical connections being adapted to cause said latch operating means to be energized upon operation of the auxiliary switching means, and to be de-energized upon operation of the relay control means.

16. A synchronous communication system comprising a typewriter having a keyboard, switching means associated with said typewriter whereby specific circuits are closed when each key of said typewriter is depressed, keyboard control means, means for transmitting periodic single synchronizing signals and aperiodic single printing signals, a transmission circuit, means for receiving the transmitted synchronizing and printing signals, an electrical energy source, means for distributing current impulses corresponding to said signals, release means for utilizing said current impulses corresponding to the synchronizing signals to establish synchronism, a second typewriter, actuating means for said second typewriter, and selector means for utilizing the current impulses corresponding to the printing signals to energize selectively the typewriter actuating means.

17. In control apparatus for printer keyboards, in combination, a keyboard having a plurality of

keys, control means associated respectively with said keys and arranged in predetermined sequence, a continuously operating member arranged to cooperate sequentially with said control means, means for transmitting a signal upon the cooperation of said continuously operating member with the control means associated with an actuated key, and non-repeat means for controlling the retention of an actuated key in actuated position until after the cooperation of said continuously operating member with the control means associated with such actuated key for preventing the transmission of additional signals upon a subsequent cooperation of said member with said control means during a single actuation of a key.

18. In control apparatus for printer keyboards, in combination, a keyboard having a plurality of keys, control means associated respectively with said keys and arranged in predetermined sequence, a continuously operating member arranged to cooperate sequentially with said control means, means for transmitting a signal upon the cooperation of said continuously operating member with the control means associated with an actuated key, means for retaining an actuated key in actuated position until after cooperation of said continuously operating member with the control means associated with such actuated key and for preventing simultaneous actuation of any of the other keys, and non-repeat means for preventing the transmission of additional signals upon subsequent cooperation of said member with said control means during a single actuation of the key.

HARRY J. NICHOLS.
